UNITED STATES PATENT OFFICE

2,059,585

ROLLING DOOR MECHANISM

Harry G. Kelly, Omaha, Nebr.

Application February 27, 1932, Serial No. 595,507

9 Claims. (Cl. 20—20)

The present invention relates to a movable support of the rollers of a sectional door and a means for moving such a door laterally at the end of its downward closing motion.

5 The objects of the present invention, among others, include the following:—

An improved hinged support for the spindles of rollers associated with the sections of a door moving outwardly and downwardly to close an opening in a wall.

10 A new spring attachment to said hinged support to hold the door inwardly away from frictional contact with the frame of said door opening except when counteracted by a superior force.

15 A new means of overcoming such inward spring action on a door and imparting instead an outward lateral displacement of the door into contact with the stops of a door frame at the end of the closing movement of the door.

A new hinged roller support for a sectional door assuring level support of the open door and movable support in its final closing and initial opening movement.

20 25 The cooperation of the above means with a counterbalancing means described in a pending application of the applicant and of Serial Number 525,572.

These and such other objects of the invention 30 as may hereinafter appear, are obtained by the novel construction, unique arrangement, and improved combination of the elements illustrated in the accompanying single sheet of drawings disclosing several forms of the invention, and in 35 which:

Figure 1 is a side elevation of a door opening and door therefor, illustrating the method of incorporating the present invention into assembly therewith;

40 Figure 2 is a fragmentary view of the present invention in side elevation and illustrating details of assembly;

45 Figure 3 is an enlarged view taken in perspective of a roller construction for the uppermost door section showing its engagement with the track and deflecting means incident to a closed position of the door;

50 Figure 4 is a perspective view of a roller construction for a lower door section as engaged with a track;

Figure 5 is an orthographic projection of the roller construction shown in Figure 4 as viewed from the side;

55 Figure 6 is a side view of an arm member of the invention and shown in broken elevation;

Figure 7 is an orthographic projection of the arm member shown in Figure 6 taken normal to that view;

60 Figure 8 is a perspective view of a cam plate

illustrating its position assumed when the door is in the open position; and

Figure 9 is a perspective view of the cam plate shown in Figure 8, illustrating its position assumed when the door is in the closed position. 5

Like reference characters are used to designate similar parts in the drawing and in the description of the invention which follows.

The invention is adapted particularly for use in a garage or an industrial building having a 10 relatively low ceiling.

In a wall 10 of a building having a relatively low ceiling (not shown) is shown a door opening 11 bounded on three sides by frame members 12 carrying stops 13 having a face 14 opposed to 15 a sectional door 15 for closing the door opening 11.

Vertical frame members 16 perpendicular to frame members 12 are secured to the wall 10 on either side of the door opening 11 and have 20 a face 17 opposed to the lateral edges of the closed door 15.

Door 15 consists of an uppermost section 18 and lower sections 19 joined together by hinges 20. For guiding the movement of door 15 from a 25 vertical position, in which the door opening 11 is closed, upwardly and inwardly to an horizontal position above the door opening 11, is a track 21 on either side of the door opening 11. The track consists of a vertical track section 22, a continuing curved track section 23, and a horizontal track section 24, the latter being for the support of the door 15 in its open position. 30

Within track 21 is an uppermost roller 25 associated with the uppermost door section 18. Other 35 rollers 26, associated with door sections 18 and 19 are also associated with the track.

In Figures 1, 2, 4 and 5 is shown a movable support 27 for lower rollers 26 of door sections 18 and 19. Rollers 26 are adapted to rotate freely on the spindles 28 extending into the sleeve 29 of a hinge member 30 carrying an opposed parallel sleeve 31. Sleeves 29 and 31 of said hinge are connected by a flat member 32. Within sleeve 31 is a spindle 33 passing through opposed holes 34 in wings 35 of a bracket 36 secured to lower door sections 19 and the lower portion of the uppermost door section 18. A stop edge 37 is articulated from the bracket 36 to abut the hinge leaf 32 in its pivotal movement to limit the movement of the door 15 toward spindle 28 at a predetermined distance from said spindle. 45

Bracket 36 carries a spring 38 with one end 39 secured to a block 39a. The other end 40 of the 50 spring makes impinging contact at 41 with the sleeve 29 of the hinge member 30 to force hinge member 30 against the stop edge 37 in the absence of any counteracting force.

55 In Figures 1, 2 and 3 is shown a movable sup-

60

port 42 for the upper portion of uppermost door section 18.

In movable support 42 there is an uppermost roller 25 adapted to rotate on a spindle 28a held by a hinge member 30a. Comprising the movable support 42 is a bracket 42a and a spring 42b similar to the brackets 36 and springs 38 of movable supports 27, the main difference being that the flat member 32a of the uppermost hinge member 30a may be wider than flat member 32 of the hinge members 30. The stop edges 37 of all brackets 36 and the stop edges 37a of the bracket 42a are placed at the same distance from door 15.

It will be noted that there is room for very little lateral movement of the rollers 25 and 26 within the track sections 22, 23 and 24 so that the hinged connection of rollers 25 and 26 with door 15 provides for a lateral movement of door 15 relative the track sections. Normally all sections of the door 15 are held parallel to track sections 22 or 24 by the action of the springs 38 and 42b as limited by stop edges 37 and 37a.

It is also evident that the projection of the spindles 28 and 28a into sleeves 29 and 29a respectively is telescopic whereby lateral expansion or contraction of door 15 may be readily accommodated.

Uppermost hinge member 30a of movable support 42 carries perpendicular to the outer edge 30 of the section 32a a flat member 44. The member 44 is perforated with a hole 45 to receive a spindle 28a, and another hole 46 to receive a spindle 33a. Flat member 44 carries along one edge a perpendicular flange 47 having a face 48 inclined downwardly toward the plane of the member 32a.

For contacting with the outer face 48 of flange 47 is a roller 49 adapted to rotate on a spindle 50. The latter may be secured to the track section 23 or to the wall 10 as desired. The spindle 50 is to be located a greater distance from door 15 than is the track section 23. As the closing motion of the door 15 nears completion, the outward face 48 contacts with the roller 49 to impart an outward motion to the uppermost spindle 33a and uppermost bracket 36a to pivot them about the spindle 28a. This pivoting motion is had against the urge of the spring 42b and results in the forcing of the upper portion of the uppermost door section 18 outwardly into weatherproof contact with faces 14 of stops 13.

Commencing with the initial upward and opening movement of door 15 the outward pressure imparted to the uppermost door section 18 by the angular contact of the angularly inclined face 48 of the flange 47 is gradually lessened to permit the inward urge of the spring 42b of the movable support 42 to draw the uppermost door section away from the stops 13.

A means for counteracting the force of the springs 38 and for forcing lower door sections 19 and the lower portion of uppermost door section 18 outwardly into contact with the stops 13 at the completion of the closing movement of door 15 is shown in Figures 1, 2, 6, 7, 8 and 9.

Attached to face 17 of frame member 16 opposite upper door section 18 is a strike plate 52 having a perpendicular flange 53 on its lower edge. Strike plate 52 furnishes a lug 54 for the anchorage of one end 55 of a spring 56 having another end 57 anchored to a movable arm 58 extending downwardly of the strike plate 52. The contractual movement of the spring 56 is limited by the abutment of the flange 53 with a similar

flange 59 along the upper edge of movable arm 58.

Projecting at intervals from a face 60 of movable arm 58 which is opposed to the lateral edge of a closed door 15 are pins 61. Pins 61 extend through slots 62 of cam plates 63 which are rotatable about pintles 64 of attachment plates 65 secured to face 17 of frame 16.

Extending perpendicularly from a face 66 of each cam plate 63 to project adjacently behind the face of a closed door 15 is a pin 67. The pin 67 is positioned below slot 62 and the pintle 64. In all cases the pintle 64 is located beyond the slot 62 toward the door opening 11.

It will be noted that any downward motion of 15 movable arm 58 will impart a rotating motion to cam plate 63 about pintle 64 by means of the engagement of the moving pin 61 with the lower edge 68 of the slot 62. Said rotating movement of the cam plate 63 about the pintle 64 located 20 upward and outward the pin 67 imparts to said pin 67 an outward motion toward the door opening 11.

A downward movement is imparted to movable arm 58 at the completion of the closing movement 25 of door 15 by the contact of the spindle 69 of the lowermost roller 26 with an upper edge 70 of an horizontal extension 71 configuring the lower end of the movable arm 58.

The extended end 73 of each pin 67 extends 30 inwardly beyond the lateral edge 74 of door 15 when the door is in a vertical position. During the initial major portion of the closing movement of the door 15, said door passes between the pins 67 and the door stops without frictional contact 35 with either.

When the closing movement of door 15 nears completion spindle 69, which projects inwardly beyond the sleeve 29, makes contact with the edge 70 of the aforesaid extension 71 to force 40 said movable arm 58 downwardly. This downward movement of the arm results in a rotation of cam plates 63 whose pins 67 are thereby moved outwardly to first contact the inner face 75 of door 15 and then force the door outwardly 45 against the urge of the springs 38 and into weatherproof contact with faces 14 of stops 13. The action just described takes place coincidentally and in full co-operation with the previously described lateral closing motion of the 50 upper portion of door section 18.

Contact plates 76 may be attached to face 75 of door 15 at each point for contact by the pins 67 therewith to prevent damage to said door by said pins.

Commencing with the initial opening movement of the door 15 the downward pressure of lowermost spindle 69 on extension 71 of movable arm 58 is gradually released thus permitting the spring 56 to raise the movable arm 58 until 60 flange 59 of said movable arm contacts with flange 53 of the strike plate 52. The upward movement of the movable arm 58 imparts to all cam plates 63 a rotating motion in a direction opposite to that effected during the final closing 65 movement of door. Hence there occurs an inward motion of the pins 67 to release the force counteracting the outward force of the springs 38 on the door 15; said door then being drawn inwardly by said springs 38 away from its 70 contiguous position with faces 14 of the stops 13.

The release of the force counteracting the inward force of lower springs 38 during the initial opening movement of door 15 just described takes place coincidentally and in full co-ope- 75

tion with the release of the force counteracting the urge of uppermost spring 38, whereby all sections 18 and 19 are withdrawn from the stops 13 simultaneously.

5 As the opening movement of the door 15 continues, the contact of the lowermost spindle 68 with extension 71 of movable arm 58 and also the contact of pins 67 with contact plates 16 of door surface 75 is broken and the forces counter-
10 acting all springs 38 being thereby removed the resultant inward movement imparted to all sections 18 and 19 of door 15 continue under the impingement of their respective springs 38 and 42b until said inward movement is stopped by
15 the contact of the stop edges 37 and 37a with the respective pintled members 32 and 32a.

The hinged members 32 and 32a which are drawn by springs 38 and 42b into respective contact with stop edges 37 and 37a, which are located a uniform distance from door 15, makes it evident that the supporting rollers 25 and 26 carried by the hinged members will be an equal distance from all door sections. This provides that the door 15 will be supported, while in its
25 open position, in an undistorted plane parallel to the horizontal track section 24.

In the application of the described closing means for the door sections 19, the movable arm 58 is placed upright a predetermined distance
30 from the floor. Strike plate 52 is attached to frame member 16 with its flange 53 in contact with the flange 59 of the movable arm 58 and spring 56 is co-anchored to the strike plate 52 and the movable arm 58.

35 Cam plates 63 are placed with their slots 62 circumjacent to the pins 61 and have an edge 71 perpendicular to face 14 of the vertical stop 13 when said door is open, said perpendicular edge 71 being a guide for the application of attachment plates 65 in uniform relation.

40 In Figure 1 the effective weight of door 15 is shown counterbalanced by a counterbalancing means fully described in the before noted and pending application of the applicant, Serial Number 525,572. In the present instance a cable 80 having one end 81 secured to a lower portion of the door 15 winds on a drum 82 coincidentally with the unwinding of another cable 83 from the drum 84, the latter rotating only in unison with
45 drum 82. The free end 85 of cable 83 is secured to one end 86 of an extensible spring 87 whose other end 88 is anchored to a fixed support 89.

What I claim is new and desire to secure by Letters Patent of the United States is:

55 1. A building having a door opening, tracks at each lateral side of said opening and extending normal thereto above said opening, a door for said opening and carried by said track, said door being adapted to be aligned with said opening, and a door closing mechanism comprising a roller for engaging said track, a bracket attached to said door and providing a stop edge, a link hingedly connected to said bracket and providing a journal for said roller, and a spring urging said door and link to swing together whereby said door is urged toward said track, said stop edge, when said door is not in aligned position with said opening being disposed to abut said link to preclude said door from coming into contact with said track under the urge of said spring, and a plurality of cam means pivoted about an axis which bears a fixed relation to the door opening, said cam means being engageable with the door whereby to urge said door horizontally forward against the door opening.

2. A building having a door opening, a sectional rolling door, a door closing mechanism in association with said door for closing said door opening, and a track for guiding said door, said door closing mechanism comprising a bracket attached to each door section, rollers affiliated with said track, hinged connecting means between said rollers and said brackets, springs, and a stop on said brackets, said springs urging said hinged connecting means to pivot about the connection thereof to said roller to urge said door toward said track when said door is not aligned with said door opening, and said stops being disposed for operation independently of said track to interrupt the movement of all of said door sections at an equal distance from said track whereby said sections assume a plane parallel to said track, and a plurality of cam means pivoted about an axis which bears a fixed relation to the door opening, said cam means being engageable with the door whereby to urge said door horizontally forward against the door opening.

3. A building having a door opening, a sectional rolling door, a door closing mechanism in association with said door, and a track for said door, said door closing mechanism comprising a bracket attached to each door section, rollers affiliated with said track, hinged connections between said rollers and said brackets and providing journals for said rollers, a bracket on said building, and a roller on said bracket, the said last mentioned roller engaging the hinge member on the uppermost door section to arrange said hinge member normally to said track whereby to project the upper section of said door into alignment with the remaining sections thereof when the door is in vertical position.

4. A building having a door opening, a door comprising superposed hinged sections for closing such opening, a track for guiding the several sections of said door from an open horizontal position above such opening to a substantially vertical position in a plane adjacent such opening, the plane of the uppermost door section being angular to the plane of the several lower sections of the door as the door approaches a position of registry with such opening, means for deflecting the several lower sections of the door in unison and in a single plane in the direction of the door opening as such position of registry is attained, and means for angularly moving said uppermost door section into sealing engagement with said opening during the movement of said door into registry with such opening, said uppermost section of said door having thereon a bracket, a member pivoted to said bracket and having a guide roller journaled therein, said guide roller being disposed in said track, resilient means upon said bracket and urging said pivoted member angularly to normally maintain said uppermost door section away from said door opening as the door is closed, and means limiting the movement of said door section under the urge of said resilient means, said means for angularly moving said uppermost door section comprising a guide means independent of said door and having a member for engaging said pivoted member coincidentally with the movement of the door into registry with such opening to change the angularity of said pivoted member relatively to said door section against the urge of said resilient means, the change in angularity between said pivoted member and said door section causing the latter to move into a sealing position with said door opening.

5. A building having a door opening, a door having superposed hinged sections for closing such opening, a track for guiding the several sections of said door from a horizontal open position above such opening to a substantially vertical position in a plane adjacent to such opening, the plane of the uppermost door section being angular to the plane of the several lower sections of the door as the door approaches a position of registry with such openings, means for deflecting the several lower sections of the door laterally into sealing relation with such door opening as such position of registry is attained, a bracket upon the uppermost section of said door, a member pivoted to said bracket and having a guide roller journalled therein, said guide roller being disposed in said track, resilient means urging said pivoted member angularly to maintain said uppermost door section away from such door opening, means limiting the movement of said door section under the urge of said resilient means, said limiting means being carried wholly upon said door and out of contact with said track, and means for angularly moving said uppermost door section against the urge of said resilient means into sealing relation with such door opening coincidentally with the movement of the door into registry with such opening.
6. A building having a door opening, a door having superposed hinged sections for closing such opening, a track for guiding the several sections of said door from a horizontal open position above such opening to a substantially vertical position in a plane adjacent to such opening, the plane of the uppermost door section being angular to the plane of the several lower sections of the door as the door approaches a position of registry with such opening, means for deflecting the several lower sections of the door laterally into sealing relation with such door opening as such position of registry is attained, a bracket upon the uppermost section of said door, a member pivoted to said bracket and having a guide roller journalled therein, said guide roller being disposed in said track, resilient means urging said pivoted member into a position parallel to said track to urge said uppermost door section away from such door opening, means limiting the movement of said door section under the urge of said resilient means, said limiting means being carried wholly upon said door, and deflecting means disposed in the path of said pivoted member and abutted thereby for angularly moving said uppermost door section against the urge of said resilient means into sealing relation with such door opening coincidentally with the movement of the door into final registry with such opening.
7. A building having a door opening, a door having superposed hinged sections for closing such opening, a track for guiding the several sections of said door from a horizontal open position above such opening to a substantially vertical position in a plane adjacent to such opening, the plane of the uppermost door section being angular to the plane of the several lower sections of the door as the door approaches a position of registry with such opening, means for deflecting the several lower sections of the door laterally into sealing relation with such door opening as such position of registry is attained, a bracket upon the uppermost section of said door, a member pivoted to said bracket and having a guide

roller journalled therein, said guide roller being disposed in positive association with said track, resilient means urging said uppermost door section and said pivoted member to swing toward one another to urge said door section away from such door opening toward said track, and means limiting the movement of said door section under the urge of said resilient means, said limiting means being movable with said door, and means for angularly moving said uppermost door section against the urge of said resilient means into sealing relation with such door opening coincidentally with the movement of the door into registry with such door opening.

8. A building having a door opening, a door having superposed hinged sections for closing such opening, a track for guiding the several sections of said door from a horizontal open position above such opening to a substantially vertical position in a plane adjacent to such opening, the plane of the uppermost door section being angular to the plane of the several lower sections of the door as the door approaches a position of registry with such opening, means for deflecting the several lower sections of the door laterally into sealing relation with such door opening as such position of registry is attained, a bracket upon the uppermost section of said door, a member pivoted to said bracket having a guide roller journalled in a section thereof and having another section projecting beyond said track, said guide roller being indisplaceably disposed in said track, resilient means urging said pivoted member angularly in one direction to urge said uppermost door section away from such door opening toward said track, means limiting the movement of said door section under the urge of said resilient means, and means for angularly moving said uppermost door section into sealing relation with such opening and comprising guide means independent of said door and having a member disposed in the path of movement of the projecting section of said pivoted member to be engaged thereby during the final part of the movement of said door into registry with such opening to move said pivoted member in the opposite direction and to advance said door section angularly against the urge of said resilient means.

9. A rolling door comprising a door opening, a track in juxtaposition to said door opening, a door comprising a plurality of hingedly connected panels, said panels being respectively hinged together along parallel lines, a plurality of roller members adapted to roll in said track, flexible connection means associated with each of said roller members, said flexible connection means being attached at one end to the roller and at the other end to the door and including means disposed therebetween to permit the door panels to move toward and away from the track, spring means associated with the flexible connection means to normally urge the door toward the track, a plurality of cam means, each of said cam means being pivotally mounted in such a manner that the axis of rotation of said cam means bears a fixed relation to the track, each of said cam means being adapted also to engage a predetermined panel of the door when the door is in juxtaposition to the door opening, and cam actuating means, said cam actuating means being operated by the action of the bottom panel of the door.

HARRY G. KELLY.
